UNITED STATES PATENT OFFICE.

SIDNEY C. WILSON, OF ROCHESTER, NEW YORK, ASSIGNOR TO WILSON PROCESS, INCORPORATED, OF ROCHESTER, NEW YORK, A CORPORATION OF NEW YORK.

PROCESS OF MAKING SHOES.

1,421,347.

Specification of Letters Patent. Patented June 27, 1922.

Application filed September 26, 1919. Serial No. 326,567.

To all whom it may concern:

Be it known that I, SIDNEY C. WILSON, a citizen of the United States, and resident of Rochester, in the State of New York, have 5 invented an Improvement in Processes of Making Shoes, of which the following description, in connection with the accompanying drawings, is a specification, like letters on the drawings representing like parts.

10 My present invention is a novel boot or shoe and I have devised an economical practical and efficient method of manufacturing my improved shoe, which method I believe is also new.

15 In my prior application, Ser. No. 317,456, filed August 14, 1919, on an improved type of insole for use in the manufacture of boots and shoes, I have therein shown, described and claimed the insole having channels 20 formed on both the grain side and flesh side. The present application is directed to cover the shoe made with the novel insole of my said prior invention, as well as the preferred process of making such a shoe embodying 25 this insole.

In the preferred method of manufacturing my improved boot or shoe, I first prepare the insole substantially as shown in said prior application, said insole being preferably of the usual type of leather insole now generally employed in the manufacture of the welt type of footwear. This insole is channelled on the flesh side by forming a flap, preferably cut from toward the center of the shoe outwardly toward the marginal portion and around the forepart and shank excepting the extreme toe portion. This extreme toe portion may or may not be channeled, as desired. On the grain side of the insole, i. e., 30 on the side or surface of the insole intended to be next the foot of the wearer in the completed shoe, I form a channel by splitting in the marginal portions of the insole, preferably leaving the toe portion unchanneled. 35 This inner channel, i. e., in the grain side, is intended to cover the through and through stitch, my present shoe being stitched on a McKay shoe stitcher. The formation of the channel on the flesh side of the insole, i. e., 40 that next the filling and outsole and in the form preferred, is believed to be distinctly new, and the provision of channels in the opposite surfaces of an insole, is also new, and intended to be covered broadly in said

prior case. These channels are preferably 55 "staggered" somewhat, so that the "between substance" will be of proper strength and practically unweakened. In utilizing this type of insole in my novel shoe, I produce a completed shoe with substantially the full 60 strength of the thickness of the insole for the stitching, holding insole, upper and outsole together. In carrying out my process I apply the appropriate insole to a last with the grain side down, this last being of the 65 usual welt last type, viz., without a clinching plate on the bottom, then assemble an upper thereon, thereupon pulling over and lasting the shoe. In this lasting process, I prefer to use the welt type of lasting machinery 70 first pulling over the toe, if desired, and thereafter lasting and tacking the sides and shank of the upper to the insole, and last by lasting tacks partly driven in. This is the welt method of lasting, 75 as distinguished from the McKay type of lasting, wherein the lasting tacks are driven entirely into and through the insole, being clinched on the inner sides of the insole against the metal plate on the bottom of 80 the last. After this lasting, I next secure the lasted upper to the insole flap on the flesh side by any suitable fastenings. Preferably I employ small metallic staples, five or six 85 being set through the edge of the lasted upper and the channel flap. With the shoe in this condition I then pull the lasting tacks, by any method, machine or by hand, identically as in the manufacture of welt shoes, thus leaving the lasted upper held in lasted 90 position by the staples. The filling may then be applied, although a relatively small amount of filling is required in my shoe, because the channel flap practically lies down close to the insole and the outsole is applied 95 directly thereto. It will be understood that at the time of lasting, the heel lasting will be completed by nailing down the heel seat and preferably also the toe is nailed down. With the shoe thus ready for the application of 100 the outsole, I may either cement the outsole or the margin of the insole or rely on the adhesive qualities of the shoe filling or filler. Then apply the outsole, then subject the shoe to the sole laying operation. The outsoles are 105 standard McKay outsoles, preferably with channels formed in the bottom or grain surface and turned back, the outsole being sub-

jected to the laying operation in a welt sole laying machine with these outsole channels turned backwardly. The shoe is now ready to be removed from the last, or as is the usual 5 term, the last is pulled, as in McKay shoe manufacturing. The shoe is now ready to be sewed by through and through stitching, a standard McKay sewing machine, such for example as the well known Rich- 10 ardson McKay sewer being used. In this step my present invention enables a very close stitch to be set. In fact, the outsole stitching may be made almost twice as closely as in ordinary McKay stitching. In 15 setting these stitches they are formed from the channel in the grain side of the insole through to the channel in the outer surface of the outsole and for this purpose the insole channel should be turned over 20 before sewing or this insole channel may be turned over when the insole is first applied to the last. The latter operation I find to be the simpler and preferable and without injury to the leather. After the through and 25 through or McKay stitching, the insole lip is then turned down, preferably using the machine of my prior application, Ser. No. 302,013, filed June 5, 1919, or any suitable manner. I find it advisable to moisten or 30 temper the insole preparatory to this smoothing and turning down operation, as will be more fully explained hereinafter.

The shoe is now complete, but it may be desirable to again use the last or follower, the 35 same last being suitable for use, and levelling the shoe on a standard welt leveller, treeing, finishing and completely the shoe in the usual manner.

Referring to the drawings illustrating my 40 improved construction and adapted to carry out my process,

Fig. 1 is a plan view of my improved insole showing the grain side or the side next to the foot of the wearer, channeled to cover the 45 McKay stitching;

Fig. 2 is a plan view of the reverse side of my improved insole, i. e., the flesh side, showing the channel flap;

Fig. 3 is a cross sectional view showing the 50 shoe in different steps during the process of manufacture on the last;

Fig. 4 is a cross-sectional fragmentary view; and

Fig. 5 is a cross sectional view showing the 55 completed shoe.

Referring to the drawings, the prepared insole as designated generally as 1, is first split in on the grain side of the forepart and shank, indicated as 2, 2, forming a 60 flap 3, 3, on each side, extending from the toe portion 4 to the heel seat 5. On the reverse side of the insole, i. e., the flesh side, is also formed the lip 6, 6, cut inwardly from the center of the insole, as indicated 65 at 7, 7, toward the marginal edge to a depth 8, slightly staggered from the line 2 of the flap on the grain side. This lip also runs from the toe portion 4 to the heel part 5, which latter are preferably uncut. The advantages, importance and usefulness of this 70 insole is still further pointed out and claimed in my said copending application, reference to which is hereby made for a fuller description of this feature. With the insole thus prepared with double channeled portions I apply the same to a last 75 10. This last may be of any suitable or desirable type or style, block last, hinge last, or otherwise, and preferably is of the standard wooden type, without clinching 80 plate excepting at the heel, as is generally employed in making welt shoes. This last, therefore, can receive the points of lasting tacks without damage or clinching the same. In applying the insole 1 to the last 10, the 85 flaps 3 may be turned over as indicated at the right of Fig. 3 or may be left as split, as shown at the left of Fig. 3, to be afterwards turned up preparatory for the sewing, as will be explained. In Fig. 3 I have 90 shown both methods. The upper materials 12 are then assembled upon the last and the shoe preferably subjected to the pulling over machine operation. This pulls over the last and tacks the toe portion of the 95 insole, whereupon the shoe is further lasted along each side and shank by any welt lasting machines or methods. I prefer to employ the usual hand method lasting machine for this operation, the machine 100 pulling over the upper and securing it to the insole and last by driving in temporary lasting tacks 14. This operation is performed exactly as in making welt shoes, by the same machines, same operations and on 105 the same labor bases and rates. With the shoe thus lasted, I then secure the marginal edge of the lasted upper to the inner lip 6, by permanent securing means 15, see Fig. 3, at the right. These fastenings may 110 be and preferably are thin metallic staples which are set through above the lasting tacks, in a well known manner, by any desired machine or by hand. Thereupon the lasting tacks 14 are removed, 115 exactly as in welt shoe manufacture, and the surplus portions of the upper and the lip 6 may then be trimmed off. This trimming, however, is entirely optional, as the lip 6 pulls down very closely to the body 120 of the insole 1, and the slight thickness of the upper materials 12 do not form much of a ridge between the two soles. In my shoe, because of this construction and the peculiar form of the lip 6 and its securing 125 staples to the upper, an intermediate filling material can be omitted, although I prefer to apply such a filler 16 on the insole, similar to welt shoe fillers now in general use. With the shoe thus completed, the 130

outsole 20 is then applied and temporarily secured to the lasted shoe, either by the adhesive qualities of the filler 16 or by additional cement coating. This outsole is 5 of usual McKay type, preferably having cut therein a channel 21 by forming a portion 22 to cover up the McKay stitching. The shoe may now be levelled and the last 10 is then withdrawn from the 10 shoe and the stitching 25 set, uniting the insole, upper and outsole in a permanent manner. This stitching is formed by the standard types of McKay stitching machines having a sewing horn, as already 15 described. Prior to the stitching operation, the portions 22 on the outsole are turned backwardly, and if the insole flaps 3 have been left as shown at the left in Fig. 3 i. e., not turned backwardly as indicated at the right of said Fig. 3, these 20 flaps are turned, the insole being first moistened and tempered. If, however, as is preferred, the flaps 3 have been turned backwardly when the insole was applied to 25 the last, the shoe is then in position for sewing without further operations. After the sewing operation, these insole flaps 3 are cemented and turned downwardly in any suitable manner, preferably by using 30 the machine of my said prior application, Ser. No. 302,013. The shoe is then re-lasted and finished, treed, and completed in the usual manner.

It will thus be seen that I have devised 35 a novel method of making an extremely flexible shoe employing the economical McKay methods so far as stitching and construction is concerned, but obtaining the advantages, also, of a welt shoe construction with the better fitting, flexibility, appearance and features of the welt shoe. Furthermore, the construction is substantially equivalent in flexibility and in the 40 preliminary operations of lasting, to turn 45 shoe work, my completed shoe, by the process herein set forth, producing resultant advantages heretofore possessed by either a welt shoe or turn shoe, and accomplished by my invention in a substantial McKay 50 shoe type of construction employing straight through and through stitching.

In the present application I have elected to claim my novel process and in my co-pending application, Ser. No. 332,222, I 55 have claimed the shoe made by this process, while in my copending case, Ser. No. 317,456, filed August 14, 1919, I have claimed broadly the novel type of insole I preferably employ.

60 By my present method of utilizing the channel lip 6 cut on the insole, in a manner to receive fasteners or fastenings, preferably in spaced position, and equivalent to "stay tacks" in welt lasting, to hold the 65 upper when lasted by welt lasting methods,

machines or processes, which lip and attached upper are of sufficient strength only to hold the lasted upper while the last is withdrawn and the through-and-through stitching applied; and furthermore which 70 lip is specially formed to lie flush with the insole from which it is temporarily lifted for the upper attaching steps, I have produced a flexible and substantially tackless McKay shoe. The further feature of forming the insole with an inner channel and flap 75 which will lie flat, cover, conceal and protect the through and through stitching, imparting to the inner surface of the insole a smooth foot contacting surface and giving 80 the appearance, comfort and desirability of a welt shoe, and yet in a through-and-through fastening construction, I am enabled to make a commercially practicable and successfully marketed boot or shoe. 85 I am advised that my invention of lasting a McKay type of shoe by welt processes, securing lasting tacks temporarily thereto, and then removing these lasting tacks, while attaching the upper to the insole with sufficient strength to hold the upper in lasted position until the through and through stitching is applied, is a distinct novelty in 90 this art, and I wish to claim the same broadly.

95 My invention is further described and defined in the form of claims as follows:

1. The improved process of making boots and shoes which consists in forming an insole with a marginal lip from the heel 100 portion to adjacent the toe on each side, assembling the insole and upper materials on a last and lasting the upper by working the upper over the edge of the insole and securing it in lasted position by means of 105 lasting tacks, partially driven in, then attaching the lasted upper by a plurality of separate fasteners to the insole lip, then removing the lasting tacks, applying an outsole and withdrawing the last, and thereupon 110 permanently uniting the outsole, upper and insole by through and through stitching, on a line between the separate fasteners and the insole edge, and thereafter finishing the shoe in any desired manner.

2. The improved process of making boots and shoes which consists in forming a lip or flap along the marginal edge portion of each face of an insole and extending from 120 the heel to the toe thereof, assembling the insole and upper materials on a last having clenching plates at toe and heel only, lasting the heel and toe portions and driving permanent lasting tacks through the upper 125 and insole and clenching them at said heel and toe portions, then working the upper over the edge of the insole and securing it temporarily by lasting tacks partially driven in, then attaching the upper 130

to one of said lips or flaps at intervals by separate fasteners, thereupon removing the temporary lasting tacks, applying an outsole, withdrawing the last, and uniting 5 the insole, upper and outsole by through and through stitching on a line between the separate fasteners and the insole edge and thereafter folding the remaining lip or flap over the exposed stitching on the in- 10 side of the boot or shoe.

In testimony whereof, I have signed my name to this specification, in the presence of two subscribing witnesses.

SIDNEY C. WILSON.

Witnesses:
